(57) CLAIM

I claim, the ornamental design for a removable underwear, as shown and described.

DESCRIPTION

FIG. 1 is a front perspective view, showing my new design;
FIG. 2 is a front and side perspective view thereof;

FIG. 3 is a front elevational view thereof;

FIG. 4 is a rear elevational view thereof;

FIG. 5 is a left plan view thereof;

FIG. 6 is a right plan view thereof;

FIG. 7 is a top plan view thereof; and,

FIG. 8 is a bottom plan view thereof.

The broken lines shown in the drawings are for illustrative purposes only and form no part of the claimed design.
